UNITED STATES PATENT OFFICE.

RALPH R. REED, OF OAKLAND, CALIFORNIA.

SAFETY DEVICE.

1,248,913.

Specification of Letters Patent.

Patented Dec. 4, 1917.

Application filed December 8, 1916. Serial No. 135,879.

To all whom it may concern:

Be it known that I, RALPH R. REED, a citizen of the United States, residing at Oakland, county of Alameda, and State of California, have invented certain new and useful Improvements in Safety Devices; and I do declare the following to be a full, clear, and exact description of the invention, such as will enable others to make and use the same.

10 This invention relates to certain new and useful improvements in devices for compelling vehicles to use slow speed at dangerous points along the road, and more especially at railroad crossings.

15 With this and other objects in view, the invention consists in certain new and novel features of arrangements and combination of parts, such as will be hereinafter described and claimed.

20 In the accompanying drawings Figure 1 is a diagram showing the intersection of a railroad E with a road for wheeled vehicles, the latter being bounded at the sides by the fences A;

25 Fig. 2 is an elevation of a peculiarly constructed panel of which six may be seen in plan, disposed in baffle formation, (three on each side of the railroad track), Fig. 1;

Fig. 3 is a vertical section on line 3—3, Fig. 2; and

Fig. 4 is a transverse section on line 4—4 Fig. 2.

Similar letters refer to similar parts throughout the several views.

35 Arranged in groups of three on each side of the railroad track, as above noted, Fig. 1, are shown peculiarly constructed panels, so located as to give to the occupants of approaching vehicles the impression of a line

40 of fencing across the road. The location, relatively, of the members of each group, in baffle formation, necessitates slow speed on the part of vehicles being driven through.

The construction of these panels is such as 45 to present a yielding surface to the impact of a swiftly moving vehicle, and one which will suffer the minimum amount of damage therefrom; but which will in turn, inflict damage to tires of carelessly driven vehicles,

50 if made of rubber. At G, Figs. 2 and 3, is shown a heavy sill, preferably of wood, having a channel H formed into its top, and all corners and surfaces at the top formed into curves. The flexible pickets B, preferably 55 of spring steel, are shown fastened to the

sill by means of lag screws, such fastening (at their bases) allowing them to yield as already described, when struck, or run over by passing vehicles. The cutting edges J are designed to gash the tires of carelessly 60 driven vehicles.

I claim:

1. The combination with a railway and a highway crossing the same, of means at staggered points in said highway for forcing vehicles traveling thereon to take a tortuous course before crossing said railway, whereby their speed must necessarily be slackened.

15 2. The combination with a railway and a highway crossing the same; of a plurality of short fences extending transversely of said highway and arranged in staggered relation, whereby slackened speed of vehicles on said highway is caused, said fences being spaced 70 sufficiently to permit the vehicle to take a tortuous course therebetween.

3. The combination with a railway and a highway crossing the same; of means in said highway for inflicting slackened speed of 75 vehicles before reaching the crossing or for puncturing the vehicle tires if ignored.

4. The combination with a railway and a highway crossing the same; of a plurality of short fences extending transversely of 80 said highway and arranged in staggered relation, whereby slackened speed of vehicles on said highway is caused, said fences being spaced sufficiently to permit the vehicles to take a tortuous course therebetween, and 90 each fence being formed of a plurality of downwardly yieldable self-righting pickets having means thereon for puncturing the tires of a vehicle if depressed by the latter.

5. The combination with a railway and a 95 highway crossing the same; of a plurality of short fences extending transversely of said highway and arranged in staggered relation, whereby slackened speed of vehicles on said highway is caused, said fences being 100 spaced sufficiently to permit the vehicle to take a tortuous course therebetween, and each fence being formed of a plurality of flexible downwardly yieldable self-righting pickets anchored at their lower ends to 105 sleepers embedded in the highway, said pickets having means for puncturing the tires of a vehicle if depressed by the latter.

6. The combination with a railway and a 110 highway crossing the same, of a downwardly

yieldable self-righting fence in said highway around which the vehicles thereon must travel.

7. The combination with a railway and a
5 highway crossing the same, of a transverse fence in said highway around which vehicles thereon must drive, whereby slackened speed is inforced, said fence consisting of a plurality of downwardly yielding self-righting pickets.

8. The combination with a railway and a
10

highway crossing the same, of a transverse fence in said highway around which vehicles thereon must drive, whereby slackened speed is inforced, said fence consisting of a 15 plurality of downwardly yielding self-righting pickets having means thereof for puncturing vehicle tires if depressed thereby.

RALPH R. REED.
